UNITED STATES PATENT OFFICE

117,003

DESIGN FOR A THROAT MICROPHONE

Albert E. Woodruff, Oak Park, and Albert F. Horlacher, Chicago, Ill., assignors to Associated Electric Laboratories, Inc., Chicago, Ill., a corporation of Delaware

Application February 2, 1939, Serial No. 82,718

Term of patent 14 years

To all whom it may concern:

Be it known that we, Albert E. Woodruff and Albert F. Horlacher, citizens of the United States of America and residents, respectively, of Oak Park, Cook County, Illinois, and Chicago, Cook County, Illinois, have invented a new, original, and ornamental Design for a Throat Microphone, of which the following is a specification, reference being had to the accompanying drawing, forming a part thereof.

We claim:

The ornamental design for a throat microphone, as shown.

ALBERT E. WOODRUFF.
ALBERT F. HORLACHER.
